Des. 217,165
Patented Apr. 14, 1970

217,165

BODY COMPONENT FOR AN ANIMAL TOY OR THE LIKE

Reuben B. Klamer, 9460 Wilshire Blvd., Beverly Hills, Calif. 90212, and Robert Y. Allen, 2372 S. Veteran Ave. 90064, and Melvin Shaw, 232 S. Veteran Ave. 90024, both of Los Angeles, Calif.

Continuation-in-part of design application Ser. No. 7,790, July 13, 1967. This application May 3, 1968, Ser. No. 11,762

Term of patent 14 years

Int. Cl. D21—02

U.S. Cl. D34—2

FIG. 1

FIG. 3

FIG. 2

FIG. 1 is a perspective view of a body component for an animal toy or the like, showing our ornamental design; FIG. 2 is a left side view thereof; and

FIG. 3 is a rear view thereof.

This application is a division of copending application Ser. No. D. 7,790, filed July 13, 1967, and abandoned.

We claim:

The ornamental design for a body component for an animal toy or the like, substantially as shown and described.
